UNITED STATES PATENT OFFICE.

EDGAR G. NEWELL, OF GLEN RIDGE, NEW JERSEY.

DESIGN FOR A BABY'S BALL-PATTERN.

SPECIFICATION forming part of Design No. 33,124, dated August 28, 1900.

Application filed May 28, 1900. Serial No. 18,334. Term of patent 7 years.

To all whom it may concern:

Be it known that I, EDGAR G. NEWELL, a citizen of the United States, and a resident of Glen Ridge, in the county of Essex and State of New Jersey, have invented and produced a certain new and original Design for a Baby's Ball-Pattern, of which the following is a specification.

Figures 1, 2, 3, 4, 5, and 6 are enlarged views of the various different sections or longitudinal segments of the unitary design for a baby's ball-pattern. Fig. 7 is a bottom or pole view of my design as an entirety for a baby's ball-pattern, so far as the unitary design can be shown in a single view. Fig. 8 is a side view, slightly inclined to the horizontal plane, of my design for a baby's ball-pattern, showing the design as an entirety, so far as it can be shown in a single view, with one of the sections, Fig. 6, in front and six of the diamond-shaped or pointed figures, hereinafter described, at the top or upper pole.

Similar reference-marks refer to similar parts or features throughout the several views.

The leading or material feature of my design consists in the shape and ornamentation of the segments of the outside surface or covering of the ball, as shown. The shape of these segments or sections follows the longitudinal lines of a globe on the sides and runs to a point at the poles or ends, and near the mid-

dle of each segment is an ornamentation in shape of an oval plaque or figure, as shown at 2.

Within each one of the oval plaques 1 is a full-length portrait or illustration of a child shown in different attitudes, with toys and other surroundings, each oval plaque and the figures and illustrations therein showing contrasting colors. Outside of and on each side of each oval plaque I have a narrow plain strip, as at 2. Above and below each oval plaque on each segment or section I have a plain part, as at 3 and 3', this plain part being tinted in different colors on different sections. At the poles or points of the sections or longitudinal segments I have a diamond-shaped part, as shown at 4 and 4', which in each section or segment is tinted in a different color from the plain part 3 and 3' of that particular section or segment.

Having thus described my invention, what I claim as new and original, and desire to secure by Letters Patent, is—

The design for a baby's ball-pattern substantially as herein shown and described.

Signed at New York, in the county of New York and State of New York, this 21st day of May, A. D. 1900.

EDGAR G. NEWELL.
